US0D1086889S

(12) **United States Design Patent** (10) **Patent No.:** **US D1,086,889 S**
(45) **Date of Patent:** **** Aug. 5, 2025**

(54) **PACKAGING WITH A BAND**

(71) **Applicant:** **Apple Inc.**, Cupertino, CA (US)

(72) **Inventors:** **Alissa Anderson**, San Francisco, CA (US); **Jonathan Berk**, Mountain View, CA (US); **Margaret Madigan Burke**, Sunnyvale, CA (US); **Jack Wanderman**, San Francisco, CA (US); **Kevin Scott Fetterman**, Los Altos, CA (US)

(73) **Assignee:** **Apple Inc.**, Cupertino, CA (US)

(**) **Term:** **15 Years**

(21) **Appl. No.:** **29/817,969**

(22) **Filed:** **Dec. 6, 2021**

Related U.S. Application Data

(63) Continuation of application No. 29/746,605, filed on Aug. 14, 2020, now Pat. No. Des. 937,686, which is a continuation of application No. 29/720,247, filed on Jan. 10, 2020, now Pat. No. Des. 893,314, which is a continuation of application No. 29/697,459, filed on Jul. 9, 2019, now Pat. No. Des. 872,578, which is a continuation of application No. 29/668,073, filed on Oct. 26, 2018, now Pat. No. Des. 856,147, which is a continuation of application No. 29/593,124, filed on Feb. 6, 2017, now Pat. No. Des. 832,103, which is a continuation of application No. 29/519,811, filed on Mar. 9, 2015, now Pat. No. Des. 778,161.

CLAIM

The ornamental design for packaging with a band as shown and described.

DESCRIPTION

FIG. 1 is a top front perspective view of a first embodiment of packaging with a band showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;
